UNITED STATES PATENT OFFICE.

CHARLES E. DAVIS, OF CHICAGO, ILLINOIS.

DETACHABLE ROSETTE.

SPECIFICATION forming part of Letters Patent No. 453,337, dated June 2, 1891.

Application filed December 31, 1890. Serial No. 376,363. (No model.)

To all whom it may concern:

Be it known that I, CHARLES E. DAVIS, a citizen of the United States, residing at Chicago, Illinois, have invented a certain new and 5 useful Improvement in Detachable Rosettes, of which the following is a full, clear, and exact specification.

My invention relates to detachable-rosette fuses that may be used in connection with 10 pendent incandescent electric lamps or other similar devices; and it consists in certain details and methods of construction whereby the liability of the rosette to become detached is reduced and the facility with which it can be 15 operated and manufactured increased. I attain these objects by mechanism illustrated in the accompanying drawings, in which—

Figure 1 shows a plan view of the base-piece of the rosette. Fig. 2 represents a plan 20 view of the cap-piece detached. Fig. 3 is the same as Fig. 1 with certain altered forms of construction. Fig. 4 is a sectional view of the cap-piece, showing a block between the contacts.

25 Similar letters of reference refer to similar parts throughout the several views.

The base-piece A of the rosette, which may consist of any suitable material, such as wood or porcelain, is depressed at its center, as 30 shown by the shaded lines in Figs. 1 and 2 at B. Radial slots are cut in the rim of the base-piece, into which are inserted the springs B', which consist, preferably, of sheet-metal stamped out and provided at its end with a 35 screw-threaded hole, into which the screw C fits. These provide means for attaching to the electric wires or mains. Near these holes are other holes C', which serve to attach these spring-contacts to the base by a screw. I do 40 not care to limit myself to any particular mode of attaching these contacts to the base. A short distance from the hole C' the contact is bent over to the side, making an angle of ninety degrees, as shown at D. This part 45 stands edge upward within the depression in the base. This is plainly seen in Figs. 1 and 3. The material from which these contacts are made is preferably elastic, so as to have a springy action. Their tendency may be in- 50 ward, and when this is so a stop D' is sometimes provided, against which the end may

rest, so as to prevent the springs from contacting with each other. The cap E, Figs. 2 and 4, is also recessed and provided with screw-terminals for securing the wires G. 55 The plates to which these wires are secured also serve to secure one end of the fuse-wires H, which place the same in electrical communication with the metallic pieces I. These pieces are furnished with screws which serve 6c to hold them in position on the cap, as will readily be seen, and then are bent so as to rise out of the recess, preferably over against each other and in such a manner as to constitute elastic or springy projecting contacts, 65 and at the extreme end are provided with outwardly-projecting lips. (Indicated at I'.) Between these lips, in Fig. 4, is shown an insulating substance K. This, though valuable for some reasons, is not necessary in all 7 cases for the proper operation of the device. The upward projections form contacts which co-operate with the springs D and are so narrow that when they are placed between the springs they do not connect one to the other; but upon turning them their faces (indicated at I'') will come in contact with the springs D and force them outwardly as they pass around the corner, and upon still further turning will at last rest directly upon the 8 face, as shown in Fig. 3, with the lips I and I' coming up back of the edges of the springs, which effectually prevents the cap from being removed from the base until it has been partially rotated. In so doing it will be withdrawn from contact. To prevent so great a rotation that the cap will again become detached, I in some cases prefer to bend the ends of the springs D, as shown at L. To still further facilitate the operation of the device, I cause a lip M to be formed about the outer edge of the base-piece of the rosette, which rises higher than the other part of the side wall of the base A. The internal border of this lip is sufficient to take in the cap, which guides the same, and especially while being rotated into position. Holes are provided in the base for the attachment of the rosette to the ceiling or other support. A conducting-cord which takes the current from the translating device, which this rosette is adapted to guard by its fuse, is brought into

the center of the cap through an aperture, as shown in Fig. 4.

The value of this detachable rosette consists in the fact that the cap may be removed and taken from the ceiling down to the floor, where the work of replacing the fuse can be done quickly and correctly, rather than standing on top of a step-ladder or other uncertain support and performing the delicate operation of replacing the fuse under a great disadvantage.

I do not care to limit myself to the exact details of construction. For instance, I have found that it is not necessary in all cases to provide the lips I' I', inasmuch as the friction of the rigid springs D against the surfaces I'' I'' is sufficient to hold the cap in position. It will also be understood that it is not necessary that the springs D and D' should be parallel to each other, as other arrangements of the position would effect the object sought equally as well, especially when considering the fact that the cap is guided effectually by the lip upon the edge of the base, as shown in the drawings.

I am aware that prior to my invention detachable rosettes have been constructed and operated; but in most cases they require to be screwed or otherwise laboriously fastened together, and in no case whatever, to my knowledge, has the spring action ever been utilized in this manner.

What I claim as new, and desire to secure by Letters Patent, is—

1. In a detachable rosette, two flat springs arranged to spring laterally, each being supported at or near one end to the edge of one element of the body of the rosette and protruding toward the interior thereof substantially parallel to each other, and upright flat contacts mounted upon the other element and adapted to engage the interior surfaces of the springs by being inserted between them and then turned until the contact-surfaces are parallel and in contact with the surfaces of the spring, in combination with laterally-projecting portions upon the upright contacts, adapted to protrude outwardly above the springs when the contact-surfaces engage, substantially as and for the purpose specified.

2. In a detachable rosette, two flat springs arranged to spring laterally, each being supported at or near one end to the edge of one element of the body of the rosette and protruding toward the interior thereof substantially parallel to each other, upright flat contacts mounted upon the other element and adapted to engage the interior surfaces of the springs by being inserted between them and then turned until the contact-surfaces are parallel and in contact with the surfaces of the

spring, and laterally-projecting portions upon the upright contacts, adapted to protrude outwardly above the springs when the contact-surfaces engage, in combination with a circular guide upon one of the elements, substantially as and for the purpose specified. 65

3. In a detachable rosette, two flat springs arranged to spring laterally, each being supported at or near one end to the edge of the base, being provided with a clamp for the line-wire at this end and protruding toward the interior thereof substantially parallel to each other, and upright flat contacts mounted upon the cap and provided at the point of mounting with circuit-wire connections and adapted to engage the interior surfaces of the springs by being inserted between them and then turned until the contact-surfaces are parallel and in contact with the surfaces of the spring, in combination with laterally-projecting portions upon the upright contacts, adapted to protrude outwardly above the springs when the contact-surfaces engage, substantially as and for the purpose specified. 80

4. In a detachable rosette, a base provided with two parallel and opposite yielding flat-surfaced springs, forming electrical contacts at one end and provided at the other with a portion which is twisted at an angle of ninety degrees thereto and provided with a screw for the purpose of attaching the line-wire, upright parallel and opposite contacts protruding from the cap, which are centrally located, the width of which is less than the distance apart of the parallel springs attached to the base and their distance apart more than this distance, and circular guiding portions between the base and cap. 95

5. In a detachable rosette, a base provided with two parallel and opposite yielding flat-surfaced springs, forming electrical contacts at one end and provided at the other with a portion which is twisted at an angle of ninety degrees thereto and provided with a screw for the purpose of attaching the line-wire, upright parallel and opposite contacts protruding from the cap, which are centrally located, the width of which is less than the distance apart of the parallel springs attached to the base and their distance apart more than this distance, and circular guiding portions between the base and cap, in combination with abutting projections engaging the free end of the springs, located upon the base of the rosette, substantially as and for the purpose specified. 110
